UNITED STATES PATENT OFFICE.

CLAUDE A. P. TURNER, OF MINNEAPOLIS, MINNESOTA.

REINFORCED CONCRETE CONSTRUCTION.

1,032,571.

Specification of Letters Patent. Patented July 16, 1912.

Original application filed January 23, 1905, Serial No. 242,431. Divided and this application filed October 20, 1910. Serial No. 588,198.

To all whom it may concern:

Be it known that I, CLAUDE A. P. TURNER, of Minneapolis, in the county of Hennepin and in the State of Minnesota, have invented 5 a certain new and useful Improvement in Reinforced Concrete Construction, and do hereby declare that the following is a full, clear, and exact description thereof.

My invention relates to the reinforcement 10 of concrete buildings and other structures in which reinforced concrete enters, and my object is to produce a structure in which beams may be dispensed with and to this end my invention consists in the reinforced concrete structure having the characteristics substantially as hereinafter specified and claimed.

In the drawings—Figure 1 is a vertical section, partly in elevation of a portion of 20 a building embodying my invention; and Fig. 2 a top plan view thereof, showing the floor slab reinforcement, the floor supporting columns being shown in horizontal section.

25 The structure shown is a building having a flat plate floor, or slab, 10 resting upon and from which rise columns 11, the floor or slab and columns being monolithic, or an integral mass of concrete. Through the 30 columns pass vertical reinforcing rods *e* bound together and which at their upper ends, within the floor or slab 10, are bent or turned laterally so that they radiate in all directions from the column forming a wide-spreading cantaliver head at the top of the 35 column.

The slab or floor reinforcement between the columns, consists of what I term main lines of reinforcement, and of supplemental 40 lighter reinforcement. The main lines are composed of groups of rods *d* that run in at least four directions through the slab, that is directly from column to column and diagonally from column to column, and which 45 cross the columns and project into the slab beyond the same. The lighter reinforcement consists of a fabric *i* of expanded metal, woven wire or netting or fencing, that is, such fabric as is customarily used for reinforcement purposes. Said fabric being extended throughout the slab and serving to fill in the area not occupied by the main lines of reinforcement, tends to provide for the tensile stresses more uniformly throughout the slab than would the main lines alone,

and said fabric and the main lines of reinforcement are preferably situated toward the bottom of the slab at the center, and toward the top of the slab over the columns or supports.

60 The column rods *e* may directly support the slab-reinforcing rods *d*, but other supporting means such as bricks laid upon the forms, or steel or other equivalent supports may be used.

65 This application is a division of my application No. 242,431 filed January 23, 1905.

Having thus described my invention what I claim is—

1. In flat plate and column construction 70 of reinforced concrete, the combination of a flat plate floor slab, columns directly supporting the same, wide spreading cantaliver heads over the columns and in the slab, main lines of reinforcement running from cantaliver head to cantaliver head and continuing beyond the same into the slab, and supplementary reinforcement extending through the slab in the spaces between the main lines of reinforcement.

75 2. In flat plate and column construction of reinforced concrete, the combination of a flat plate floor slab, columns directly supporting the same, wide spreading cantaliver heads over the columns formed of rods and 80 extending into the slab in all directions from the columns, sets of rods passing through the slab from column to column and extending above said cantaliver heads into the slab to points beyond the columns, and slab reinforcement lighter than said rods extending through the slab in the spaces between the main lines of reinforcement.

85 3. In flat plate and column construction 90 of reinforced concrete, the combination of a flat plate floor slab, columns supporting the same, wide spreading cantaliver heads over the columns and in the slab formed of rods, main lines of reinforcement running directly and diagonally from cantaliver head to cantaliver head, and continuing beyond the same into the slab, and supplementary reinforcement extending through the slab in the spaces between the main lines of reinforcement.

100 4. In flat plate and column construction 105 of reinforced concrete, the combination of a flat plate floor slab, columns supporting the same, wide spreading cantaliver heads over the columns forming circumferential cantaliver heads.

- livers, sets of rods extending in the slab and constituting main lines of reinforcement running from column to column directly and diagonally and continuing beyond the same,
5 the rods crossing at the top of the columns, and a supplemental fabric-form reinforcement extending through the slab in the spaces between said rods and resting upon said rods, said rods and fabric being nearer
10 the bottom of the slab between the columns and nearer the top of the slab over the columns.
5. In flat plate and column construction of reinforced concrete, the combination of a
15 flat plate floor slab, columns supporting the same, wide spreading cantaliver heads over the columns forming circumferential canta-

livers, sets of rods extending in the slab and constituting main lines of reinforcement running directly and diagonally from column to column, said lines of reinforcement continuing beyond the column and into the slab, the rods crossing at the top of the columns and head, supplementary reinforcement extending through the slab in the spaces between the main lines of reinforcement and tending to distribute the tensile stress throughout the slab. 20 25

In testimony that I claim the foregoing I have hereunto set my hand.

CLAUDE A. P. TURNER.
